UNITED STATES PATENT OFFICE.

FREDERICK A. SEITZ, OF NEWARK, NEW JERSEY.

INTERNAL-COMBUSTION ENGINE.

1,283,331.

Specification of Letters Patent. Patented Oct. 29, 1918.

Application filed July 27, 1917. Serial No. 183,106.

To all whom it may concern:

Be it known that I, FREDERICK A. SEITZ, a citizen of the United States, residing at the city of Newark, Essex county, in the State of New Jersey, have invented certain new and useful Improvements in Internal-Combustion Engines, of which the following is a full, clear, and exact specification.

My invention relates to improvements in internal combustion engines, and the same has for its object more particularly to provide a simple, efficient and reliable engine by means of which a higher efficiency, and a greater degree of perfection in operation may be obtained:

Further said invention has for its object to provide an engine in which the cubical contents of the cylinder may be automatically increased during the compression and explosive periods, and automatically decreased during the exhaust period.

Further said invention has for its object to provide an engine from which all of the burnt gases will be discharged from the cylinder after each explosion, thus preventing the new charge being diluted by any burnt gases which would otherwise remain in the cylinder.

Further said invention has for its object to provide an engine having comparatively simple, and positively actuated valve mechanism.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings, showing an illustrative embodiment of the invention;

Figure 1 is an end view, partly broken away and in section, of an engine constructed according to and embodying the invention;

Fig. 2 is a plan view thereof;

Fig. 3 is a detail sectional view of the cylinder head taken on the line 3—3 of Fig. 2, and

Fig. 4 is a detail view of the mechanism for actuating the displacer piston.

Referring to the drawings, 10 indicates the cylinder of the engine, having its lower end secured to a crank casing 11, and hav-

ing a head 12 secured to its upper end. Within the cylinder 10 works a piston 13 provided with a piston rod 14, having its lower end connected to the main crank shaft 15, to the outer end of which is fixed a fly wheel 16. A gear wheel 17 secured to the crank shaft 15 meshes with a gear wheel 18 secured to a cam shaft 19 rotatably mounted within the casing 11.

The head 12 is provided with a fuel inlet opening 20 and an exhaust outlet opening 21. The head 12 is further provided with an intake port 22 and an exhaust port 23 adapted to establish communication between the cylinder 10 and the inlet and outlet openings 21 and 22 respectively. Co-acting with the intake and exhaust ports 22, 23, are intake and exhaust valves 24, 25, provided with valve stems 26, 27, which extend outwardly through the head 12. The valves 24, 25 are normally maintained in position to close the intake and exhaust ports 22, 23, by springs 28 surrounding the upper ends of the valve stems 26, 27 and having their ends engaging the head 12 and washers 29 positioned upon the valve stems 26, 27, and held in place by nuts 30 threaded thereupon.

Within the head 12 is a secondary cylinder 31 the upper end of which is in communication with the space or passage between the inlet opening 20 and the intake port 22, and the lower end of which is in communication with the cylinder 10. Working within the secondary cylinder 31 is a displacer piston 32 provided with a piston rod 33 extending outwardly through the head 12. At its upper end, the secondary cylinder is provided with a seat 31' with which the piston 32 engages, when in its uppermost position, to form a gas-tight joint.

The intake valve 24 is controlled, in its opening and closing movement, by a lever 34 pivotally supported, intermediate its ends, upon the head 12 and having one of its ends engaging the upper end of the valve stem 26, and its other end connected to the upper end of a rod 35, the lower end of which engages a cam 36 secured to the cam shaft 19. The movement of the exhaust valve 25 is controlled by similar mechanism consisting of a lever 37 engaging the valve stem 27 and connected to a rod 38, the lower end of which engages a cam 39 also secured to the cam shaft 19.

The piston rod 33 of the displacer piston

32 is connected, at its upper end, to one end of a lever 40, pivotally supported intermediate its ends upon the head 12, and having its other end connected to the upper end of a rod 41. The rod 41 extends through a sleeve 42, within the casing 12, and has secured to its lower end a head 43 engaging a cam 44 secured to the cam shaft 19. The head 43 is provided with a shoulder 45 engaged by one end of a coiled spring 46, the other end of which engages the under surface of a collar 47 slidingly mounted upon the sleeve 42. Pivotally supported within the casing 12 is a cam actuated follower 48 having a forked end 49 engaging the upper surface of the sliding collar 47 and having its other end 50 engaging a cam 51 secured to the cam shaft 19.

The cams 44 and 51 are so shaped, and so arranged upon the cam shaft 19, that the follower 48 will be actuated by the cam 51 to cause its forked end 49 to be depressed, thus forcing the collar 47 downwardly and compressing the spring 46, as the displacer piston 32 is moved upwardly during the suction stroke of the piston 13, thereby insuring that the head 43, secured to the rod 41, will be positively held in engagement with its co-acting cam 44 during the upward movement of the displacer piston 32. During the compression stroke of the piston 13 the collar 47 and follower 48 will be moved in the opposite direction to occupy their normal positions, by the action of the spring 46, in which positions they will remain until the next succeeding compression stroke of the piston 13.

The operation of the engine is as follows:

40 Referring to Fig. 1, the parts are shown in the position which they occupy at the completion of the exhaust stroke of the piston 13, the displacer piston 32 being in its lowermost position, the intake valve 24 being closed, and the exhaust valve being open, in order that the burnt gases may pass from the cylinder 10 through the exhaust port 23 and through the exhaust outlet opening 21. It will be seen that there is practically no space within which the burnt gases may lodge thus insuring that all of the gases will be expelled from the cylinder 10. As the upper end of the secondary cylinder communicates with the space or passage between the inlet opening 20 and the intake port 22, it will be seen that when the displacer piston 32 is in its lowermost position the effective cubical contents of such space is increased thereby permitting a greater quantity of the explosive mixture to be introduced into the head 12 than would be the case if such space were not increased.

As the piston 13 descends in making its suction stroke, the exhaust valve 25 will be

closed and the intake valve 24 will be opened, thus permitting the fresh charge of the explosive mixture to pass from the head 12 into the cylinder 10. During the suction stroke of the piston 13 the displacer piston 32 will be raised to its uppermost position, thereby forcing the explosive mixture which is within the head 12 to pass therefrom and into the cylinder 10. The upward movement of the displacer piston 32 within the secondary cylinder 31 will create a suction which will augment the suction caused by the downward movement of the piston 13 within the cylinder 10, thus insuring the drawing into the cylinder 10 of a greater charge of the explosive mixture than would be drawn in by the suction caused by the piston 13 acting alone. In view of the fact that the contents of the space within the head 12 between the inlet opening 20 and the intake port 22 was increased by the movement of the displacer piston 32 to its lowermost position, as above described, it will be understood that the charge introduced into the main cylinder 10 will be greater than if the contents of such space were not increased. During this stroke the follower 48 will be actuated to compress the spring 46 thus insuring that the head 43 on the rod 41 will be held firmly against the cam 44, as above explained.

In the operation of the displacer piston 32 it is moved practically to its uppermost position by the cam mechanism, and is then yieldingly maintained in said position until the moment of compression, when the compressed gases will serve to move said piston upwardly for the remainder of its movement, viz: about one eighth of an inch, and cause the same to seat properly upon its seat 31' at the upper end of the secondary cylinder 31. The cam mechanism is so designed and arranged as to permit of this action, and thereby avoid the undesirable noise or hammer effect which would otherwise result from the seating of said displacer piston.

As the piston 13 begins to make its compression stroke, the intake valve 24 will be closed, the exhaust valve 25 being maintained closed, and the displacer piston 32 being maintained in its uppermost position within the secondary cylinder 31, in which position the displacer piston 32 engages the seat 31', thereby forming a gas-tight joint and preventing any leakage during the compression and explosion periods. During the compression stroke the explosive mixture will be compressed within the cylinder 10 and the cylinder 31. The charge is then exploded in the usual manner by a spark plug 52 and the piston 13 is forced downwardly, the valves 24 and 25, and the displacer piston 32 remaining in the positions occupied

by them during the compression stroke. As the piston 13 makes its next upward, or exhaust stroke, the exhaust valve 25 will be opened and the displacer piston 32 will be moved to its lowermost position, thus forcing the burnt gases out of the cylinder 31 and insuring the exhaust of all of the burnt gases from the interior of the engine. The downward movement of the displacer piston 32 will create a suction within the head 12 thereby drawing a fresh charge into the head 12 through the inlet opening 20.

With the operation last above described the fourth cycle of the operation of the engine is completed, and the various operations above described will thereafter be repeated in the sequence stated.

Having thus described my said invention what I claim and desire to secure by Letters Patent is:

1. In an internal combustion engine, the combination with a main cylinder having intake and exhaust ports and valves therefor, a piston within said main cylinder, a secondary cylinder having its opposite ends communicating with said main cylinder and with said intake port respectively, a displacer piston within said secondary cylinder, said valves being independent of said displacer piston, and means for actuating said valves and said displacer piston, substantially as specified.

2. In an internal combustion engine, the combination with a main cylinder having intake and exhaust ports and valves therefor, a piston within said main cylinder, a secondary cylinder having its lower end communicating with said main cylinder and its upper end communicating with said intake port, a displacer piston within said secondary cylinder, said valves being independent of said displacer piston, and means for actuating said valves and said displacer piston, substantially as specified.

3. In an internal combustion engine, the combination with a main cylinder having intake and exhaust ports and valves therefor, a piston within said main cylinder, a secondary cylinder communicating with the inlet opening of the engine and with said main cylinder, a displacer piston within said secondary cylinder, said valves being independent of said displacer piston, and means for actuating said valves and said displacer piston, substantially as specified.

4. In an internal combustion engine, the combination with a main cylinder having intake and exhaust ports and valves therefor, a piston within said main cylinder, a secondary cylinder having its upper end communicating with the inlet opening of the engine and with said intake port and having its lower end communicating with said main cylinder, a displacer piston within

said secondary cylinder, said valves being independent of said displacer piston, and means for actuating said valves and said displacer piston, substantially as specified.

5. In an internal combustion engine, the combination with a main cylinder provided with an intake port communicating with the inlet opening of the engine, of a piston within said main cylinder, a valve co-acting with said port, means for actuating said valve, and means for varying the cubical contents of said main cylinder and simultaneously varying the cubical contents of the passage between said intake port and said inlet opening, substantially as specified.

6. In an internal combustion engine, the combination with a main cylinder provided with an intake port communicating with the inlet opening of the engine, of a piston within said main cylinder, a valve co-acting with said port, means for actuating said valve, and means for decreasing the cubical contents of said main cylinder and simultaneously increasing the cubical contents of the passage between said intake port and said inlet opening, and vice versa, substantially as specified.

7. In an internal combustion engine, the combination with a main cylinder having a piston therein, of a secondary cylinder communicating with said main cylinder, a displacer piston within said secondary cylinder, cam and spring controlled means for actuating said displacer piston, and means for varying the tension of said spring, substantially as specified.

8. In an internal combustion engine, the combination with a main cylinder having a piston therein, of a secondary cylinder communicating with said main cylinder, a displacer piston within said secondary cylinder, cam and spring controlled means for actuating said displacer piston, and automatically operated means for varying the tension of said spring, substantially as specified.

9. In an internal combustion engine, the combination with a main cylinder having a piston therein, of a secondary cylinder communicating with said main cylinder, a displacer piston within said secondary cylinder, a rod operatively connected to said displacer piston and adapted to be moved to reciprocate said piston, a rotatable cam co-acting with said rod to control the movement thereof, a spring to hold said rod in engagement with said cam, and means to vary the tension of said spring during the rotation of said cam, substantially as specified.

10. In an internal combustion engine, the combination with a main cylinder having a piston therein, of a secondary cylinder communicating with said main cylinder, a displacer piston within said secondary cylinder,

- 4
- a rod operatively connected to said displacer piston and adapted to be moved to reciprocate said piston, a rotatable cam co-acting with said rod to control the movement thereof, a spring to hold said rod in engagement with said cam, and means to increase the tension of said spring during the travel in one direction of said displacer piston, substantially as specified.
- 10 11. In an internal combustion engine, the combination with a main cylinder having a piston therein, of a secondary cylinder communicating with said main cylinder, a displacer piston within said secondary cylinder, a rod operatively connected to said displacer piston and adapted to be moved to reciprocate said piston, a rotatable cam co-acting with said rod to control the movement thereof, a spring to hold said rod in engagement with said cam, and means to increase the tension of said spring during the travel of said displacer piston in a direction away from said main cylinder, substantially as specified.
- 15 12. In an internal combustion engine, the combination with a main cylinder having a piston therein, of a secondary cylinder having its lower end communicating with said main cylinder, and having a seat adjacent
- 20 25 30 its upper end, a displacer piston within said secondary cylinder, and means for actuating said displacer piston and maintaining the same in engagement with said seat during the compression and explosion periods of
- said first mentioned piston, substantially as specified.
13. In an internal combustion engine, the combination with a main cylinder and a piston therein, of a secondary cylinder, a displacer piston in said secondary cylinder, an intake port and an exhaust port for said engine, a passage connecting the contiguous open ends of said main and secondary cylinders with said intake and exhaust ports, valve mechanism in said passage, means for actuating said valve mechanism and said displacer piston whereby initially to draw an explosive charge into the outer end of said secondary cylinder, thence forcing said charge from the outer end of said secondary cylinder and into the inner end of said secondary cylinder, compressing the explosive charge and firing the same therein, and then causing said main piston and displacer piston to approach each other to the extreme of their opposing movements whereby to evacuate completely the contents of said cylinders during the exhausting period, substantially as specified.

Signed at the city of New York, in the county and State of New York, this 3rd day of July, one thousand nine hundred and seventeen.

FREDERICK A. SEITZ.
